UNITED STATES PATENT OFFICE.

ALVAH O. LATIMER AND WILLIAM D. CRENSHAW, OF CEDAR RAPIDS, IOWA.

BEER-PUMP ATTACHMENT.

SPECIFICATION forming part of Letters Patent No. 620,463, dated February 28, 1899.

Application filed May 16, 1898. Serial No. 680,888. (No model.)

To all whom it may concern:

Be it known that we, ALVAH O. LATIMER and WILLIAM D. CRENSHAW, citizens of the United States, residing at Cedar Rapids, in the county of Linn and State of Iowa, have invented certain new and useful Improvements in Beer-Pump Attachments; and we do hereby declare the following to be a full, clear, and exact description of the invention, such as will enable others skilled in the art to which it appertains to make and use the same.

The object of this invention is to provide a cheap, simple, and efficient device for supplying air-pressure to beer-kegs and the like; and the nature of the invention is fully disclosed in the description and claim following, reference being had to the accompanying drawings, forming a part of this specification.

In the drawings, Figure 1 is a side view of the device as applied to a beer-keg. Fig. 2 is a central longitudinal section of the device in a vertical plane and a fragment of the adjacent keg.

Similar letters of reference indicate corresponding parts.

In the drawing of beer contained in barrels, casks, and kegs it is necessary from time to time to inject into the vessel air until a considerable pressure is obtained. This is commonly done with a device known as a "beer-pump," a somewhat complicated and quite expensive apparatus. The device embodying this invention is designed to accomplish the same purpose by very simple and inexpensive means, as will appear from the description following.

Referring to the drawings, A designates an ordinary beer-keg provided with the usual faucet B. In some suitable hole near the up-

per part of the keg—the head, for example—40 is inserted a hollow metallic plug C, suitably tapered so as to be driven tightly in place and closed at the outer larger end by a head C'. At one side of the plug, near the closed end or in the end itself, if preferred, is placed 45 a small check-valve C², adapted to connect with the terminal coupling of a small air-pump D.

In practice the check-valve is of the kind commonly used for bicycle-tires, and any bicycle air-pump may be used for inflation. The pump may remain attached to the check-valve or "nipple," as it is generally called, or detached, the compressed air being retained by the check-valve, as in the case of a pneumatic tire.

It will be observed that the outer end of the plug is inset, so that in driving the plug home the blows fall on the edge of the conical tube and not on the head, which is secured in the tube in some simple manner, as by soldering.

Having thus described our invention, what we claim as new, and desire to secure by Letters Patent, is—

The herein-described air-pump attachment for beer-kegs and the like, composed of a tapered metallic tube, an inset head secured in the larger end, and a check-valve near said head, adapted to connect with an air-pump.

In testimony whereof we affix our signatures in presence of two witnesses.

ALVAH O. LATIMER.
WILLIAM D. CRENSHAW.
